UNITED STATES PATENT OFFICE.

SHOZABURO KAWAI, OF NEW YORK, N. Y.

GAME.

Application filed November 3, 1921. Serial No. 512,431.

To all whom it may concern:

Be it known that I, SHOZABURO KAWAI, a subject of the Emperor of Japan, and a resident of the city, county, and State of New York, have invented certain new and useful Improvements in Games, of which the following is a specification.

My invention relates to a game which may be used for public amusement at amusement 10 resorts and parks or it may be used in the home. The object of my invention is to provide a game in which a ball is caused to take an irregular and uncertain course and finally come to rest upon a support having a number 15 of sockets or recesses in any of which the ball may finally stop. These sockets are designated for different values or different counts in the game and are so grouped that one recess in a group will have greater value 20 in the prizes awarded or in the score or count of the game. When the ball is started in its course of travel in the game it strikes a foraminous body or screen having openings slightly larger than the ball. This 25 screen is resilient in order that when the ball strikes the wires thereof it, the ball, will rebound and return again to the screen before it settles down sufficiently to pass through the mesh, and this makes the course 30 of the ball very uncertain and irregular and increases the interest in the game. In the fullest embodiment of my invention, I arrange a plurality of these screens so that the ball passes through them in succession and 35 the screens are arranged out of vertical register in order that as the ball passes through an aperture in one it is most certain to bounce on the one below.

In the drawing forming part of this application,

Figure 1 is a vertical sectional view of a game embodying my invention,

Figure 2 is a plan view thereof,

Figure 3 is a sectional view on an enlarged scale, taken on the line 3-3 of Figure 1,

Figure 4 is a similar view taken on the line 4-4 of Figure 5, and

Figure 5 is a sectional view, on an enlarged scale, taken on the line 5-5 of Figure 1.

I have shown a cage 1 to confine the ball while passing through its irregular course and in the drawing this cage comprises in part, the four upright posts 2 having feet 3 to rest upon a table, the floor, or any other

support. Connected between these several posts, on four sides of a rectangle, are the horizontal rods 4 which are arranged sufficiently close to prevent the ball which is used in the game from passing between them. At the bottom of the cage I arrange a base 5 the details of which will be described hereinafter.

The ball is introduced into the top of the cage either by dropping it from the hand or by dropping it with any mechanical device, not shown. Near the upper portion of the cage I have arranged a screen 6 crosswise of the cage so that a ball dropped into the cage will strike on it. This screen, preferably of wire, mesh, is shown attached around its edges to bars 7 mounted between the several posts 2. The screen is inherently resilient so that if the ball strikes on any of the wires 8 thereof the resiliency of the screen will cause the ball to bounce upwardly and return again to the screen and these operations continue until the ball comes down in register with one of the openings 9 of the screen or until the ball settles down in its bounding action and rolls through one of the screen openings. When the ball passes through this screen (in a game having all the features here shown) it strikes on a screen 10 arranged below the first screen. This second screen is supported on bars 11 like the first one and it is also resilient. When the ball strikes this second screen it rebounds and goes through actions resembling its actions on the screen 6. This second screen is so positioned that its wires are out of register with the wires of the screen 6 as viewed from the top as in Figure 3. Therefore, when the ball passes through an opening in the screen 6 it is most certain to strike the wires of the lower screen 10 and thus bound on this latter screen before passing through it.

After passing through both screens, the ball falls onto the base 5. This has a surface 12 over which the ball may roll but at different positions the base has ball retaining means which, in the present showing, consists of curved recesses. These recesses are arranged in groups. For instance, the several recesses 13, arranged around a recess 14 form one group, and the recesses 15, arranged around the recess 16 form another group; and so on, over the whole base. The recesses of one group are designated differently from those of the other groups. For

instance, all the recesses 13 of the group A may be painted red, those of the group B green, etc. One recess of each group is specially designated. For instance, the central recess 14 of the group A may be colored red whereas the surrounding recesses 13 of the same group are colored blue; or, this central recess may be specially designated by a star or a number.

10 Operation: The ball is allowed to fall onto the upper screen 6, whereupon it bounces on the wires of this screen moving over the screen until it comes down in line with one of the apertures or until it settles 15 down enough to roll through an opening. It then falls onto the second screen 10 and the actions here are more or less a repetition of what took place on the first screen. From the second screen the ball falls on the base 20 5 and it rolls around on its surface 12 and in many cases the ball will fall into one of the many recesses. I prefer to use an indicating or spotting board 17 in conjunction with the game. This has spaces 18 marked 25 off and colored to correspond with the coloring of the group of recesses on the base 5. It likewise has numbers or letters 19 corresponding with the numbers of the several groups of recesses A, etc. The player first 30 deposits a coin on one of the spaces 18 of the board 17, or places any article thereon to indicate which group of recesses he believes the ball will come to rest in. If there are several players each one will select one of 35 the spaces 18 and place something there to indicate his or her choice. Then the ball is dropped in the manner above described, and it finally comes to rest in one of the recesses on the base 5. If the ball finally stops 40 in one of the recesses in group 1, then the

player who selected the corresponding space on the board 17 will score on this play or will win a prize. If the ball stops in one of the recesses 13 of the group A then the player will receive a prize of lesser value or will score some lesser count in the game, but if the ball stops in the specially designated recess 14 of the group A the winner of the play will receive a prize of greater value or will score some higher count than if the ball stopped in one of the recesses 13.

Having described my invention, what I claim is:—

1. A game comprising a base or tray on which a ball is adapted to be received and having means for holding the ball in various designated positions, and means for causing the ball to take an irregular course in passing to said base, including a plurality of resilient screens arranged one above the other and on which the ball is adapted to be dropped, said screens having a number of apertures through any of which the ball may pass in its course to said base.

2. A game comprising a base or tray on which a ball is adapted to be received and having means for holding the ball in various designated positions, and means for causing the ball to take an irregular course in passing to said base, including a plurality of resilient, mesh screens arranged one above the other and with the wires of their meshes arranged out of vertical register, the said screens being adapted to have the ball dropped thereon, whereby the ball is caused to pass successively through the apertures of both screens.

Signed at the city, county and State of New York, this 25th day of October, 1921.

SHOZABURO KAWAI.
